UNITED STATES PATENT OFFICE.

THOMAS SCANTLIN, OF EVANSVILLE, INDIANA.

ADJUSTABLE MANTEL-PIECE.

SPECIFICATION forming part of Letters Patent No. 245,095, dated August 2, 1881.

Application filed January 3, 1881. (No model.)

To all whom it may concern:

Be it known that I, THOMAS SCANTLIN, a citizen of the United States, residing at Evansville, in the county of Vanderburg and 5 State of Indiana, have invented a new and useful Improved Adjustable Mantel-Piece, of which the following is a specification.

My invention relates to improvements in adjustable mantel-pieces; and the objects of my 10 invention are, first, to provide a mantel-piece with adjustable shelf and jambs adapted to fit a variety of sizes of chimney; second, to provide adjustable jambs to the fire-place opening adapted to increase or diminish the size of 15 the fire-place and fit a variety of sizes of grate-baskets. These objects I accomplish by the mechanism illustrated in the accompanying drawings, in which—

Figure 1 represents a front elevation of the 20 entire device, and Fig. 2 is a rear elevation of the same.

Similar letters refer to like parts throughout the several views.

A A represent an ordinary mantel-piece, 25 with the usual fire-opening between the legs A' A' and the central part, B, of the shelf made fast to the front.

The side jambs, D D', of the mantel-piece are provided with slots a a a a, through which 30 the bolts b b b b pass which secure the said jambs to the rear side of the mantel-piece A and permit the lateral adjustment of said jambs. The slots a a a a are covered by metal plates I I I I when the bolts b b b are made 35 fast.

The upper ends of each side jamb, D D', are made fast to the sliding parts C C' of the shelf. The ends of these parts C C' nearest the center of the mantel pass under the central stationary part, B, of the shelf, and slide 40 between the top of the mantel-front A and the lower side of the stationary shelf B, thus admitting of the shelf C C' being adjusted laterally with the side jambs, D D', and increase 45 or diminish the length of the compound shelf O B C'.

On the rear side of the mantel-front A A, Fig. 2, is a guide, K, secured in a horizontal position to form a guide for the upper ends 50 of the adjustable side jambs, G G', of the fire-place to operate in. The upper ends of these side jambs, G G', are curved to correspond with the fire-opening in the mantel-front, and are provided with slots n n, in which are bolts 55 with nuts m m, which are used to secure the

upper ends of the adjustable jambs G G' in any desired position. The lower ends of the adjustable side jambs, G G', operate in guides r r, formed on or attached to the rear side of the legs A' A' of the mantel-front A. 60

The adjustable jambs G G' are each provided with one or more projections, d d, on which the grate-basket H is hooked, as shown.

It is obvious that the jambs D D' and the adjustable end shelves, C C', may be adjusted 65 to fit a great variety of chimneys that the mantel-piece could not be adapted to; also, that the adjustable fire-place jambs G G' may be adjusted to make a large fire-place, suitable for burning wood, or a small fire-place to 70 receive a coal-basket for burning coal.

What I claim as new, and desire to secure by Letters Patent, is—

1. A mantel-piece having a stationary front, A A, and central stationary shelf, B, combined with the adjustable end shelves, C C', by means of which the mantel-shelf may be made longer or shorter, as required, substantially as shown and described. 75

2. A mantel-piece having a stationary front, A A, and central stationary shelf, B, combined with adjustable end shelves, C C', and adjustable side jambs, D D', whereby the length of the shelf and the side jambs may be adjusted, substantially as shown and described. 80 85

3. A mantel-piece having a stationary front, A A, with legs A' A', combined with the adjustable side fire-place jambs, G G', having lugs d d for supporting the coal-basket, substantially as shown and described. 90

4. In a mantel-piece, the combination of the stationary front A A and stationary central part, B, of the shelf, the adjustable side shelves, C C', the adjustable side jambs, D D', and the adjustable fire-place jambs G G', with 95 lugs d d, all substantially as shown and described.

5. In a mantel-piece, the adjustable side jambs, G G', of the fire-place, by means of which coal-baskets of various sizes may be 100 used, and a large or small fire-place formed, as desired, substantially as described.

In testimony whereof I have signed my name to this specification in the presence of two subscribing witnesses.

THOMAS SCANTLIN.
